UNITED STATES PATENT OFFICE.

THOMAS A. SULLIVAN AND JOSEPH A. YOUNG, OF NEW YORK, N. Y., ASSIGNEES TO BROOKLYN COOPERAGE COMPANY, OF BROOKLYN, NEW YORK.

BARREL-TRUSSING MACHINE.

No. 909,705.

Specification of Letters Patent.

Patented Jan. 12, 1909.

Application filed April 4, 1908. Serial No. 425,092.

To all whom it may concern:

Be it known that we, THOMAS A. SULLIVAN and JOSEPH A. YOUNG, citizens of the United States, residing in the city of New York, borough of Brooklyn, county of Kings, and State of New York, have invented certain new and useful Improvements in Barrel-Trussing Machines, of which the following is a specification.

Our invention is designed to simplify and cheapen the manufacture of barrels provided with wire bilge hoops. Heretofore it has been the custom to truss bilge and end truss rings on the barrel in one trussing machine, pass the barrel to the crozing and chamfering machine, then knock off the bilge truss rings, substitute wire bilge hoops, and truss the latter in a second trussing machine, after which the end truss rings were removed and replaced usually by wire and wooden hoops driven by hand.

By means of our improved construction of trussing machine we are enabled to dispense with the second trussing machine above referred to, together with the time and labor involved in its use, thereby simplifying manipulation and economy in cost of production,—the usual bilge rings being removed from the barrel body and the bilge wire hoops being substituted in lieu thereof prior to placing the barrel body in the trussing machine.

The invention consists in the construction and arrangement of parts hereinafter described and claimed specifically, a distinguishing feature being the use of pivotally mounted segmental bilge-hoop drivers arranged to yield radially with relation to the barrel over and in contact with the bilge surface of which they travel in such a manner as to maintain touch with the comparatively small diameter of wire of which such bilge hoops are usually made. An incidental feature consists in the employment of gravity dogs for holding the barrel until the centralizing parts have cleared the ends of the latter during the retractile movement of the trusser mechanism, as hereinafter set forth.

In the accompanying drawings, Figure 1, is a side elevation of a trussing machine to which our improvements are applied; Fig. 2, is a central vertical sectional elevation of the right hand portion thereof; Fig. 3, is a plan of the machine; Fig. 4, a transverse

section thereof upon plane of line 4—4 Fig. 3; Fig. 5, is an elevation of the barrel as "set up" with the usual truss rings upon it; Fig. 6, is a similar view showing the bilge wire hoops substituted for the bilge truss rings; Fig. 7, is a side elevation of the central portion of the machine with the trussing mechanism advanced; Figs. 8 and 9, are detail views upon a larger scale illustrating the action of the bilge hoop drivers; Fig. 10, is a detail view illustrating the action of the bilge hoop drivers in adapting themselves to irregularities in the barrel staves; Fig. 11, is a detail view of one of the gravity dogs in action; Fig. 12, is a face view of one of the driving rings, partly in section; Fig. 13, is a view of the reverse side of a portion of one of the driving rings; Fig. 14, is a sectional elevation upon plane of line 14—14 Fig. 12; Fig. 15, is an isometrical view of certain parts of one of the bilge hoop driver mounts; Figs. 16, 17 and 18, are detail views of the retaining dog members.

The trussing mechanism at either end of the apparatus is essentially the same, so that the description and lettering applies to duplicate parts except where otherwise specified.

F represents the frame work on which the operative parts are mounted.

P is the power shaft mounted on bearings f, f, at each end of the frame, and on a pillow block f', between which and the adjacent end of the frame, said power shaft carries the usual driving and clutch mechanism A, controlled manually by the hand lever a, and connections. Worm pinions p, (see particularly Fig. 2) on the main shaft P, engage with worm gears B, on transverse shafts b, which are mounted in bearings f', on the side members of the frame F. Vertical yokes b', are suspended upon the transverse shafts b, and afford end supports for upper and lower guide rods b². These yokes b', are also rigidly attached to the outer ends of the guides G, formed with lateral extensions g, which are attached to the side members of the frame F. The guides G, support cam plungers c, carrying cam rollers c', which rest in the grooves c², of the cam C. Rigidly attached to the inner ends of the cam plungers c, are the cross heads D which are also connected with, and slide upon, the guide rods b². These cross heads are also formed with side flanges d, which rest in

horizontal grooves in brackets f^3 , of the frame F, thereby relieving the guide rods b^2 , preventing torsional strain, and lateral play. The end truss ring drivers d' , are situated 5 upon and project centrally from the cross heads D.

The bilge hoop driving rings E, are supported on the cross heads D, by means of spacing sleeves e, and bolts e', each ring E 10 having mounted upon it a series of radially arranged segmental bilge hoop drivers H, hereinafter described more fully and which constitute a distinguishing feature of our invention,—the bilge hoop driving rings E being substituted for those heretofore used for 15 driving the bilge truss ring.

The barrel centralizing cross heads I, are mounted slidably upon the guide rods b^2 , and having rigidly attached to them cam rods i, i, 20 journaled in bearings g' , on the lateral extensions g, of the guides G. The outer ends of the cam rods i, are provided with vertical shoes i^2 , against which the wiper cams J act,—said wiper cams being mounted on the 25 transverse shafts l, and being timed ahead of the cams C, so as to advance the centralizing cones i^3 , on the cross heads I, just prior to the advance of the driving mechanism. These centralizing cross heads are retracted 30 by the bilge hoop driving rings E when the latter is retracted by the cam C.

The retaining dogs R which hold the barrel temporarily during the retractile movement of the driving mechanism until the 35 centralizing cones i^3 , clear the ends of the barrel, are mounted upon sleeves S slidable upon the guide rod b^2 . The sleeves S are formed with arms s, which embrace the rack bars T (rectangular in cross section) which 40 are pivotally supported at their outer ends on posts t, rigidly attached to the guide rods b^2 . Springs t', attached to said posts t, and to the sleeve S tend constantly to hold the latter in contact with the cross head I. 45 Teeth t^2 , on the under side of the rack bars T, engage with knife edges s', on the sleeve S, the weight of the said pivoted bars T tending to maintain such engagement. When the cross heads I, and bilge hoop 50 driver rings E, are advanced, the bars T yield to permit a corresponding advance of the sleeves S, but they hold the sleeves S in their advanced positions during the retractile movements of said cross heads I and 55 driver rings E, until rollers t^3 , on said cross heads I, encounter the inclined surfaces t^4 , on the undersides of the bars T, thereby raising said bars sufficiently to release the sleeves S, and allow them to be returned by 60 the springs t', to their normal positions, resting against the cross heads I. This dogging mechanism has been used heretofore in connection with the bilge truss rings,—the novelty in the present case in this connection, 65 consisting in substituting yielding or gravity

dogs, for the rigid dogs heretofore used to temporarily engage the bilge truss rings for the purpose above stated.

The dogs R as used by us consist of segmental concave bearings r, pivotally attached to yokes r', mounted slidably between flanges s^2 , on the under sides of the sleeves S. In the drawings the vertical play is shown as provided for above these flanges s^2 , the pins s^3 , upon which the yokes r', are 75 suspended projecting above said flanges, as will be understood by reference to Figs. 16, 17 and 18. By pivotally attaching the concave segmental bearings r, to the radially yielding yokes r', said bearings are free to 80 adapt themselves to any inequality of bilge surface and still maintain contact with a hoop wire of small diameter.

Any desired number of our bilge wire 85 hoop drivers H, may be arranged radially on each ring E. Each driver consists essentially of a concave segmental shoe or bearing piece h, pivotally attached to a slide h', which is resiliently mounted on the ring E.

The object of pivotally attaching the bearing shoe h, to the slide h', is to enable it to 90 adapt itself to inequalities of surface owing to imperfect alinement of staves, as illustrated diagrammatically in Fig. 10. Thus all danger of "jumping" or over-riding the 95 wire hoop is obviated, and a continuous contact assured with the smallest diameter of wire while the hoop is being driven over the bilge.

The object of supporting the bearing shoe 100 h, on a resiliently mounted slide h', is to enable the driver to yield radially with relation to the barrel as the wire hoop is driven over the bilge, so as to afford a uniform support to the wire hoop from the beginning 105 to the end of the operation of trussing. This is insured because contact is maintained, with the bilge surface, so that a hoop made of a very small diameter of wire may be used. At the same time the machine is adapted for 110 thus trussing more than one size of barrel.

It is obvious that various mechanical expedients may be resorted to in this respect with like result, and we do not confine ourselves strictly to the identical form and construction of parts herein described, although the drawings show mechanism which has been actually and successfully employed by us in the manufacture of barrels provided 115 with wire bilge hoops.

As shown in the drawings each concave bearing shoe h is pivotally secured to a U-shaped slide h', the parallel members of which rest in a box m, which is secured in a recess e^2 , in the ring E, by means of a binding screw e^3 . This admits of the boxes and drivers being set and adjusted radially with relation to the sizes of the barrels to which the wire hoops w, are to be applied. Interposed between the cross member of the U- 120

shaped slide h' , and the upper closed end m' , of the box m , is a coiled spring n , which tends constantly to thrust the slide inward toward the center of the ring E . This outward thrust is limited by set nuts h^2 , on the outer threaded end of a stud h^3 , projecting from the cross member of the U-shaped slide h' , and through a hole m^2 , in the end m' , of the box m . These set nuts h^2 , afford means of adjusting the thrust of the slide h' , with accuracy. m^3 , is a cover for one side of the box m .

In operation the barrel as set up with both end truss rings and bilge truss rings in place as in Fig. 5, is fired, and the bilge truss rings g , are then removed and the wire bilge hoops w , substituted in lieu thereof as in Fig. 6, when the barrel is introduced into the machine and the wire hoop trussed simultaneously with the trussing of the end truss rings u . The ends of the barrel are then crozed and chamfered in the usual manner, the end truss rings u , removed and hoops substituted as heretofore.

What we claim as our invention and desire to secure by Letters Patent is,

1. In a machine of the character designated, the combination with the barrel end trussing mechanism, of a bilge hoop truss ring formed with a plurality of radially yielding resilient mounted drivers, whereby contact is maintained with the bilge surface of a barrel during the operation of trussing a wire hoop thereon, and gravity dogs for holding the barrel until the centralizing devices have cleared the ends of the barrel.

2. In a machine of the character designated, the combination with the barrel end trussing mechanism of a bilge hoop truss ring formed with a plurality of radially yielding drivers each formed with a pivotally attached segmental bearing shoe whereby contact is maintained with the bilge surface of a barrel during the operation of trussing a wire hoop thereon, and gravity dogs for holding the barrel until the centralizing devices have cleared the ends of the barrel.

3. In a machine of the character designated, the combination with the barrel end trussing mechanism, of a bilge hoop truss ring formed with a plurality of radially yielding resilient mounted drivers, whereby contact is maintained with the bilge surface of a barrel during the operation of trussing a wire hoop thereon, and gravity dogs for holding the barrel until the centralizing devices have cleared the ends of the barrel, and means for independently regulating the radial thrust of each of said wire bilge hoop drivers, for the purpose described.

4. In a machine of the character designated, the combination with the barrel end trussing mechanism, of a bilge hoop truss

ring formed with a plurality of radially yielding drivers each formed with a pivotally attached segmental bearing shoe whereby contact is maintained with the bilge surface of a barrel during the operation of trussing a wire hoop thereon, and gravity dogs for holding the barrel until the centralizing devices have cleared the ends of the barrel, and means for independently regulating the radial thrust of each of said wire bilge hoop drivers, for the purpose described.

5. In a machine of the character designated, the combination with trussing mechanism, of two opposed retaining dogs and sleeves carrying said dogs and arranged to yield to maintain contact with the bilge of a barrel, for the purpose described.

6. In a machine of the character designated, a radially-yielding slide, and a concave segmental bearing shoe pivoted to said slide.

7. In a machine of the character designated, a radially-yielding U-shaped slide, and a concave segmental bearing shoe pivoted to said slide.

8. In a machine of the character designated, a hoop driving ring, radially-yielding slides carried thereby with means for normally thrusting said slides toward the center of the ring, and concave segmental bearing shoes pivoted in said slide.

9. In a machine of the character designated, a hoop driving ring, radially-yielding slides carried thereby with means for normally thrusting said slides toward the center of the ring, concave segmental bearing shoes pivoted in said slides and means for adjusting the thrust of said slides.

10. In a machine of the character designated, centralizing devices, driving mechanism, and retaining dogs constructed and arranged to hold the barrel temporarily during the retractile movement of the driving mechanism till the centralizing devices have cleared the ends of the barrel.

11. In a machine of the character designated, centralizing devices, hoop driving mechanism, retaining dogs constructed and arranged to hold the barrel temporarily during the retractile movement of the driving mechanism till the centralizing devices have cleared the ends of the barrel, and sleeves carrying said dogs, and yielding bars co-operating with said sleeves.

12. In a machine of the character stated, a radially yielding positively-guided slide, and a segmental bearing shoe centrally pivoted to the end of said slide.

THOMAS A. SULLIVAN.
